UNITED STATES PATENT OFFICE.

WILLIAM SPARKS, OF JACKSON, MICHIGAN, ASSIGNOR TO THE SPARKS-WITHINGTON COMPANY, OF JACKSON, MICHIGAN, A CORPORATION OF MICHIGAN.

ROTARY FAN.

1,072,189.

Specification of Letters Patent.

Patented Sept. 2, 1913.

Application filed October 17, 1911. Serial No. 655,187.

To all whom it may concern:

Be it known that I, WILLIAM SPARKS, of Jackson, in the county of Jackson, in the State of Michigan, have invented new and 5 useful Improvements in Rotary Fans, of which the following, taken in connection with the accompanying drawings, is a full, clear, and exact description.

This invention relates to certain improvements in rotary fans adapted to be used more particularly with the gas engines of 10 automobiles for circulating air around and cooling the cylinders. When used in this relation they are necessarily placed in the 15 small space between the engine and grill work or radiators in the end of the hood and owing to the fact that they are driven at high speed and together with the adjacent parts of the machine are subjected to 20 more or less severe vibration due to the jolting of the machine in passing over uneven roads, the fan is liable to contact with the 25 radiator or other parts of the machine and thereby damage or destroy one or the other of the contacting parts.

My object, therefore, is to provide a one-piece sheet metal fan with a rim in which all portions of the blades are within the 30 planes of opposite sides or edges of the rim so that the rim will act as a fender to protect the blades against contact with adjacent objects.

Another object is to utilize portions of the 35 rim for bracing the otherwise unattached portions of the blades and thereby maintaining these portions of the blades at their adjusted angles against deflection by impact with the air, thus increasing the efficiency of the fan and further reducing liability to 40 injury.

Other objects and uses will be brought out in the following description.

In the drawings Figures 1 and 2 are opposite face views of my improved fan. Figs. 45 3 and 4 are respectively an edge view partly broken away and a sectional view of the same fan the latter being taken on line 4—4, Fig. 2.

This fan preferably consists of a one-piece 50 sheet metal plate circular in form and having its marginal edge deflected laterally at substantially right angles to the main body —1— for forming an annular flange —2— of sufficient width to cover the lateral de-

fection of the outer ends of the blades —3—. 55 These blades are formed by cutting away portions of the plate at —4— and then shearing the plate circumferentially from the same side of each of the openings —4— close to the rim or annular flange —2— 60 across the greater portion of the width of the blade, leaving the outer end of the blade integrally united by a comparatively narrow neck —5— to the rim, while the inner ends of the blades are connected by a continuous central web —6— having a central opening —7— for receiving a shaft, hub, or other support upon which the fan may be mounted for rotary movement. The greater portions of the outer ends of the blades are 70 therefore separated from the rim by slits —8—, thereby allowing these portions of the blades to be deflected or bent laterally from one side to a point in proximity to the opposite side of the rim as shown more 75 clearly in Figs. 3 and 4, the points of the blades being disposed in close proximity to the inner face of said rim.

Portions of the rim adjacent the points of the blades in contact therewith are indented 80 or stamped inwardly at —9— into contact with the points of the blades to brace and hold these portions of the blades which are otherwise unsupported against lateral vibration or deflection by impact with the air during 85 rotation of the fan, said indentations being shown more clearly in Fig. 2. These blades are of uniform shape and size, preferably tapering and of greater area than the intervening spaces and are spaced equi-distant 90 apart circumferentially with their wider ends adjacent the rim and all portions thereof wholly within the planes of the opposite sides of the rim so that when the fan is in operation, the rim serves as a fender to 95 prevent contact of the blades with adjacent portions of the machine or other objects.

What I claim is:

1. A fan consisting of a one-piece sheet metal circular plate having its marginal edge bent laterally at substantially right angles thereto for forming a guard flange, the main body of the plate having portions thereof cut away to form a series of blades and intervening openings, the openings being of less radial length than the radius of the fan, leaving a central web uniting the inner ends of the blades, the outer ends of

the blades being separated from the rim by slits extending in the same direction from the openings at one edge to a point in proximity to the opposite edge of the blades, 5 leaving relatively narrow webs uniting the outer ends of the blades to the rim, the portions of the outer edges of the blades which are separated by the slits from the rim being deflected laterally and means for connecting 10 the deflected portion of the blades to the rim.

2. A fan consisting of a one-piece sheet metal circular plate having its marginal edge bent laterally at substantially right 15 angles thereto for forming a guard flange, the main body of the plate having portions thereof cut away to form a series of blades and intervening openings, the openings being of less radial length than the radius of 20 the fan, leaving a central web uniting the inner ends of the blades, the outer ends of the blades being separated from the rim by slits extending in the same direction from the openings at one edge to a point in proximity 25 to the opposite edge of the blades, leaving relatively narrow webs uniting the outer ends of the blades to the rim, the portions of the outer edges of the blades which are separated by the slits from the rim being deflected laterally to points in close 30 proximity to the opposite edge of the rim, said rim having portions thereof depressed inwardly against the points of the blades.

3. A fan comprising a sheet metal plate 35 and a laterally extending rim therefor, a series of radially extending blades formed from said plate and a portion of each blade attached to the rim, the portion of each blade unattached to the rim being deflected 40 laterally, and means for connecting the de-

flected portion of said blade to the adjacent portion of the rim.

4. A fan consisting of a one-piece, sheet metal circular plate having its marginal edge bent laterally at substantially right 45 angles thereto for forming a guard flange, the main body of the plate cut to form a series of blades of less radial length than the radius of the fan, leaving a central web, portions of the outer ends of the blades being separated from the rim by slits of less 50 length than the width of the blade, leaving a relatively narrow web uniting the outer ends of the blades to the rim, the portion of the blades separated from the rim by slits 55 being deflected laterally, and means for connecting the deflected portions of the blades to the rim.

5. A fan consisting of a one-piece, sheet metal circular plate having its marginal edge bent laterally at substantially right 60 angles thereto for forming a guard flange, the main body of the plate cut to form a series of blades of less radial length than the radius of the fan, leaving a central web, 65 portions of the outer ends of the blades being separated from the rim by slits of less length than the width of the blade, leaving a relatively narrow web uniting the outer ends of the blades to the rim, the portion of the blades separated from the rim by slits 70 being deflected laterally, and means in connection with the rim for supporting the deflected portions of the blades.

In witness whereof I have hereunto set 75 my hand on this ninth day of October, 1911.

WILLIAM SPARKS.
